UNITED STATES PATENT OFFICE

WALTER C. LINDEMANN, OF MILWAUKEE, WISCONSIN, ASSIGNOR TO A. J. LINDEMANN & HOVERSON COMPANY, OF MILWAUKEE, WISCONSIN, A CORPORATION OF WISCONSIN

BROILER

Application filed July 22, 1927, Serial No. 207,852. Renewed December 30, 1931.

The improvements relate to broilers adapted to be used in connection with gas ovens and stoves, but may, with suitable modifications, be employed in electrically heated and other stoves. The principal object of the improvements is to provide a broiler of simple, efficient and convenient construction and operation which may be quickly and easily placed in position and arranged for use in the stove, or removed therefrom, so that when it is not in use it may, if desired, be entirely removed from the stove and stored away so that it will not become damaged or fouled by soot, and dirt or by food being cooked on the stove top or in the oven.

The improvements are illustrated in the accompanying drawings, in which—

Fig. 1 is a front perspective view of a gas oven and supporting frame with the broiler embodying the improvements in position there; and

Fig. 2 is a similar view of the oven bottom with the broiler opened and partly removed therefrom.

The oven 1 may be of any suitable form and should be provided with oven heating burners and broiling burners (not shown) in its bottom. These are not a part of the present improvements, which are designed to be used with ovens and burners of any satisfactory character. The oven is supported on frames 2 at either end thereof, and these frames in turn may be supported on the stove top.

To the bottom of the oven 1 are fixed a pair of substantially U-shaped tracks 3 horizontally arranged and adapted to receive the horizontal flanges 5 of the broiler compartment so that the entire broiler may be moved to position under the oven bottom and removed thereon. The flanges 5 extend across the front of the broiler compartment as well as along its sides. They do not, however, necessarily extend across the back and terminate at the rear edge of the compartment, so that the latter may be entirely removed from the oven bottom without manipulating any connection.

The broiler compartment consists of two sides 6, a back 7 and a bottom 8 which is provided with perforations 9 at the front. To

the front edge of the bottom a door 10 is hinged, so as to open downwardly to give the user access to the interior of the broiler compartment and a view thereof without drawing the latter out, and also to permit the insertion and removal of the pan 11, which is adapted to be removed and replaced at different levels on the slides 12. At the upper corners of the door hooks 13 are provided to engage over the pins 14 projecting laterally from the sides of the broiler near the top, to hold the door in closed position, and at the bottom corners of the door are downwardly extending lugs 15 which engage the bottom of the broiler compartment when the door is opened to horizontal position and hold it. The door is provided with a handle 15' by which it may be opened and closed, and by which the broiler may also be entirely withdrawn from the stove.

It will be seen from the foregoing description, that by the present improvements a broiler in one compact unit, which may be removed and replaced and stored away when not in use, is provided.

At each side of the compartment at the forward end and near the bottom a hinge member 16 is secured. This member has a cup-like extension 16' which receives the ends of a hinge pin 17 on the inner edge of the door and extending laterally therefrom. The recess of the cup is somewhat larger than the end of the pin, and therefore permits it to move to a certain extent therein, so that when the door is closed the hooks 13 will be permitted to raise the door a little in passing over their pins 14. This also brings the lower edge of the door and the lower edge of the compartment into close contact.

I claim:

1. In a cooking range, the combination of an oven, spaced trackways mounted thereon, a broiler compartment having an open top and open front, slidable means operatively associated with said compartment and cooperating with said trackways to support said compartment, the walls flanking said open front having ledges protruding inwardly therefrom, a removable broiling pan supported on said ledges, a hinged door on

- said compartment adapted to close said open front and to support the withdrawn pan when open, and said slideable means and trackways constructed to afford complete removal of said compartment from said oven.
- 5 2. In a cooking range, the combination of an oven, spaced trackways thereunder, a broiler compartment having an open top and open front, slideable means operatively associated with said compartment and cooperating with said trackways to support said compartment, the walls flanking said open front having ledges protruding inwardly therefrom, a removable broiling pan supported on said ledges, a hinged door on said compartment adapted to close said open front and to support the withdrawn pan when open, and said slideable means and trackways constructed to afford complete removal of 10 said compartment from beneath said oven.
- 15 3. In combination with an oven, a cooking compartment comprising a sliding broiler drawer, cooperating sliding means on said drawer and beneath said oven respectively for affording free travel of said drawer relative to said oven, the forward wall of said drawer being hinged at the bottom whereby it may be raised and lowered relative to said drawer, a handle on said forward wall whereby said drawer may be moved by sliding or said wall may be swung relative to said drawer, ledge members fixed to the interior side walls of said drawer adapted to suspend a broiler pan therebetween, the arrangement being such that the hinged forward wall, when horizontally disposed, may serve to support articles such as a broiler pan.
- 20 4. In combination with an oven, spaced trackways disposed beneath said oven, a broiler compartment having an open top and open front, means on said compartment and engaging said trackways for affording sliding of said compartment relative to said oven, a combined door and support hinged to the compartment and positioned for closing same when in vertical position and for serving as a horizontal support when in open position, spaced trackways disposed on opposite sides of the interior walls of said compartment, said trackways being spaced from the bottom of said compartment whereby a broiler pan may be suspended therebetween.
- 25 5. In combination with a cooking range, spaced trackways disposed thereon, a broiler compartment having an open top and front, means on said compartment and engaging said trackways for affording sliding of said compartment relative to said range, a combined door and support hinged adjacent the bottom of said compartment and positioned for swinging downwardly to open position and upwardly to close the open front of said compartment, spaced trackways disposed at the interior sides of said compartment and being spaced from the bottom thereof, a removable broiling pan supported on said last named trackways, said compartment being removable from said first named trackways and said pan being removable from said second named trackways.
- 30 6. In combination with a cooking range, spaced trackways disposed thereon, a broiler compartment having an open top and front, means on said compartment and engaging said trackways for affording sliding of said compartment relative to said range, a combined door and support hinged adjacent the bottom of said compartment and positioned for swinging downwardly to open position and upwardly to close the open front of said compartment, spaced pan-holding racks disposed on the interior sides of said compartment and spaced from the bottom thereof, a removable broiling pan supported on said racks and being slideable longitudinally on said racks through the front of said broiler compartment.
- 35 Witness my hand this 15th day of July, 1927, at the city of Milwaukee, in the county of Milwaukee, State of Wisconsin.
